(57) **CLAIM**

The ornamental design for a slip cover, as shown and described.

DESCRIPTION

FIG. 1 is a front perspective view of a slip cover showing my new design;

FIG. 2 is a top view thereof;

FIG. 3 is a bottom view thereof;

FIG. 4 is a front view thereof;

FIG. 5 is a rear view thereof;

FIG. 6 is a left side view thereof; and,

FIG. 7 is a right side view thereof.

The broken line showing of environmental structures, namely the couch and couch cushions in FIG. 1, is for illustrative purposes only and forms no part of the claimed design.

1 Claim, 2 Drawing Sheets

FIG. 1

FIG. 2

FIG. 3

FIG. 4

FIG. 5

FIG. 6

FIG. 7
